GARAGE DOOR OPENER

William T. Kahliff, Elyria, Ohio

Application March 5, 1936, Serial No. 67,383

1 Claim. (Cl. 268—59)

This invention aims to provide a novel means for opening and closing the door of a building, such as a garage. The invention aims to provide a carriage of novel form, operatively connected with the door or doors of the garage, and to supply novel means for actuating the carriage at the will of an operator.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows, in top plan, a device constructed in accordance with the invention, parts being in section;

Fig. 2 is a side elevation wherein parts are in section;

Fig. 3 is a section on the line 3—3 of Fig. 1;

Fig. 4 is a section on the line 4—4 of Fig. 1;

Fig. 5 is a perspective view showing the anchor piece;

Fig. 6 is an elevation of the motor, parts of the brake being in section;

Fig. 7 is a diagrammatic view illustrating the circuit;

Fig. 8 is an elevation showing a modification wherein a torque clutch is employed;

Fig. 9 is an elevation showing how the device may be applied to a horizontally swinging door, rather than to the vertically and horizontally slidable door of Fig. 2;

Fig. 10 is a cross section on the line 10—10 of Fig. 9.

The numeral 1 marks a building, such as a garage, having a doorway 2. The garage 1 is provided with inverted L-shaped guides 3 (Fig. 2). A door 4 for the doorway 2 is provided and has rollers 5 or other projections which move in the guides 3, the construction being such that the door 4 can be raised and slid horizontally into the dash line position of Fig. 2, in a well known manner.

A platform 6 is supported at 7 in the garage 1, in spaced relation to the doorway 2, a standard 8 being mounted on the platform. A track 9,

which may be an inverted channel, is secured at its inner end to the standard 8 and is secured at its outer end by a bracket 10 to the garage 1, above the doorway 2.

A carriage 11 is mounted to move along the track 9 and has fixed upper axles 12 on which are journaled rollers 14 adapted to ride on the upper edges of the track 9, the rollers having flanges 15 that engage the outer lateral surfaces of the track 9. Spacing sleeves 16 are mounted on one of the axles 12, between the corresponding rollers 14. The carriage 11 carries a lower axle 17, on which are journaled rollers 18 engaging the bottom of the track 9, the rollers 18 having flanges 18' that engage the outer lateral surfaces of the track 9.

The numeral 20 designates a two-part approximately L-shaped connection having at its upper end a fork 19 pivoted on the axle 17, between the rollers 18. The lower, forward end of the connection 20 is pivotally joined at 21 to the door 4. On one side of the carriage 11 there is a lateral projection 22 having sloping end surfaces.

The projection 22 on the carriage 11 is adapted to engage a forward crank arm 23 or a rear crank arm 24 on a shaft 26, the crank arms 23 and 24 being adjustably secured at 25 to the shaft 26. The shaft 26 is journaled in bearings 27 on the track 9.

On the inner end of the shaft 26 there is a crank arm 28 pivoted to a link 29 that is pivoted to the arm 30 of a switch 31 supported by a bracket 32 on the standard 8. A pull spring 33 is anchored at one end on one of the bearings 27 and is connected to the link 29.

A fixed forward shaft 34 is mounted on the track 9. The standard 8 has extensions 35 in which is journaled a rear shaft 36. There are sprocket wheels 37 which are carried by the shafts 34 and 36, one sprocket wheel being journaled on the shaft 34, and the other sprocket wheel being secured to the shaft 36 to rotate therewith. A sprocket chain 39 is engaged with the sprocket wheels 37. A channel-shaped anchor piece 38 is secured to one run of the sprocket chain 39. The anchor piece 38 carries a pivot element 40 on which is mounted one end of a link 41. The opposite end of the link 41 is pivoted on one of the axles 12 of the carriage 11, between the spacing sleeves 16.

The rear shaft 36 carries a worm wheel 42 meshing with a worm 43 on the shaft of an electric motor 44 mounted on the platform 6. A wheel 45 on the shaft of the motor 44 is engaged by a

brake shoe 46 having an armature 47 responsive to a solenoid coil 48 on the platform 6. When the solenoid coil 48 is energized, the brake shoe 46 is retracted from the wheel 45 on the shaft of the motor 44. A compression spring 49 within the coil 48 engages the armature 47 and serves to maintain the brake shoe 46 engaged with the wheel 45 on the shaft of the motor 44.

The motor 44 is interposed in a normally open 10 first motor circuit 50, in which is interposed a normally open switch 51, located at any convenient place outside the garage 1, a normally open switch 52 being interposed in the first motor circuit 50, and being located at any convenient 15 place within the garage 1. The switches 51 and 52 are under the control of an operator. The motor 44 also is interposed in a normally open second motor circuit 53, including a portion of the first motor circuit 50. The second motor circuit 53 is adapted to be closed by the switch 31 that, in its turn, is under the control of the carriage 11. The coil 48 of the motor brake is interposed in a conductor 54, connected to the first motor circuit 50 on opposite sides of the 20 motor 44. All of the various circuits and conductors may be suitably housed, as shown at 55 in Fig. 2.

Considering, first, the mechanical means for opening and closing the door 4, suppose that the 30 door is in the closed position of Fig. 1. The motor 44 operates the worm 43, the worm 43 rotates the worm wheel 42, the shaft 36 is rotated and motion is transmitted to the sprocket chain 39 by the sprocket wheel 37 on the shaft 36. The 35 sprocket chain 39 carries the anchor piece 38 backwardly, the link 41 draws the carriage 11 backwardly along the track 9, and the connection 20 raises the door 4 and slides it backwardly to open position on the guides 3.

40 The motor 44 is not reversed, but continues to rotate in one direction. The anchor piece 38 on the sprocket chain 39 is carried around onto the run of the sprocket chain 39 that is shown uppermost in Fig. 1. The carriage 11 moves to 45 the left in Fig. 1, back into the position of Fig. 2, and the connection 20 closes the door 4.

Passing to the control features, when the door 50 is in the closed position of Fig. 2 the switch 31 is held open, because the crank arm 23 on the shaft 26 rests against the projection 22 on the carriage 11. Switches 51 and 52, under the control of an operator, also are open. The solenoid coil 48 is not energized, and the spring 49 thrusts the brake shoe 46 against the wheel 45 on the 55 shaft of the motor 44.

Assuming that the operator is outside the garage 1, he operates the switch 51 of Figs. 2 and 7, to close the first motor circuit 50. The motor 44 thus is energized and put into operation. At 60 the same time, current flows through the conductor 54, and the solenoid coil 48 moves the brake shoe 46 out of engagement with the wheel 45 on the shaft of the motor 44. The carriage 11 is moved to the right from the position of Fig. 7, the operator keeping the switch 51 closed until the projection 22 on the carriage 11 is clear of the crank arm 23 on the shaft 26. Then the switch 51 may be released by the operator. The spring 33 rotates the shaft 26, and the arm 24 65 on the shaft 26 is swung inwardly toward the track 9, so as to be in the path of the projection 22 on the carriage 11. When the shaft 26 is rotated by the action of the spring 33, the switch 31 is closed by the action of the arm 28, the link 29, and the arm 30 of Fig. 4. The second cir-

5 cuit 53 through the motor 44 is energized, and the motor continues to operate, to carry the carriage 11 to the right in Fig. 7.

When the carriage 11 has proceeded far enough to the right in Fig. 7 to open the door into the dash line position of Fig. 2, the projection 22 on the carriage engages the crank arm 24 on the shaft 26 and rocks the shaft, the second motor circuit 53 being opened by the switch 31, and the door stopping in the opened position shown in dash line in Fig. 2. The flow of current through the conductor 54 is stopped at this time, the coil 48 is deenergized, and the spring 49 of Fig. 6 applies the brake shoe 46 to the motor 44.

If the operator wishes, he can go outside of the garage, operate the switch 51 again, and cause the carriage 11 to move to the left, into the position of Fig. 2. If the operator wishes, he can stay within the garage 1 and operate the switch 52, the door being closed again.

It is not necessary to use the structure in connection with the slidable door 4 of Fig. 2. In Figs. 9 and 10, parts hereinbefore described have been designated by numerals previously used, with the suffix "a". In this form of the invention, the door 4a is hinged at 56 to the building 1a. Longitudinally adjustable links 57 are pivoted at 58 to the lower portions of the carriage 11a. The forward ends of the links 57 are pivoted at 59 to the doors 4a. The construction, obviously, is such that horizontally swinging doors, or one horizontally swinging door, can be operated, as well as the vertically slidable door 4 of Fig. 2.

In Fig. 8, parts hereinbefore described have 35 been designated by numerals previously used, with the suffix "b". The modification here shown provides a clutch engagement between the rear shaft 36b and the corresponding worm wheel 42b. The worm wheel 42b has a hub 60 in which the shaft 36b may rotate, if too great a strain is thrown on any part of the mechanism. The worm wheel 42b, however, is coupled to the shaft 36b in the normal operation of the machine by a mechanism including a collar 61 secured at 62 to the shaft 36b. The collar 61 has an upwardly extended arm 63, against which abuts one end of a resilient friction band 64 extended around the hub 60 of the worm wheel 42b. A bolt 65 or the like extends through the said end of the band, and through the arm 63 on the collar 61. The opposite end of the band 64 is slidable on the bolt 65. A nut 66 is mounted on the bolt 65. A compression spring 67 surrounds a portion of the bolt 65, one end of the compression spring abutting against the nut 66, and the opposite end of the compression spring abutting against the adjacent end of the band 64, and tending to tighten the band around the hub 60 of the worm wheel 42b, the worm wheel thus being coupled to the 40 shaft 36b, in the ordinary operation of the device, but it being possible for the worm wheel 42b and the shaft 36b to have relative rotation if too great a strain is thrown on some part of the mechanism, for instance, if something happens to be below the door 4, as the door 4 descends, or between the doors 4a of Fig. 9, as those doors are closed.

50 What is claimed is:

A device for opening and closing a door, comprising a track in the form of a channel having upstanding flanges, a carriage having wheels mounted to move along the upper edges of the flanges of the track, means for connecting the carriage to the door which is to be opened and 55

closed, an endless sprocket chain extended lengthwise of the bottom of the track and housed between the flanges, means for connecting one run of the sprocket chain to the carriage, means 5 for mounting the sprocket chain, including a first shaft supported for rotation, a one-way motor, a driving connection between the motor and the first shaft, a second shaft supported on one of the flanges of the track, externally of the track, 10 for rocking movement and extended lengthwise of the track, upstanding arms on the second shaft, an outstanding cam projection on one side of the carriage, yieldable means for rocking the second shaft in one direction to dispose the arms in such position that they will be in the path of the cam projection, the cam projection then engaging the arms, one at a time, and rocking the second shaft in an opposite direction, means under the control of an operator for starting the motor, and mechanism for stopping the motor when the second shaft is rocked in said opposite direction by engagement between the cam projection and either arm. 10

WILLIAM T. KAHLIFF.
